HENRY HELM, OF PITTSBURG, PENNSYLVANIA.

Letters Patent No. 65,571, dated June 11, 1867.

FEED-CUTTER.

The Schedule referred to in these Letters Patent and making part of the same.

TO ALL WHOM IT MAY CONCERN:

Be it known that I, HENRY HELM, of Pittsburg, in the county of Allegheny, and State of Pennsylvania, have invented a new and useful improvement in Feed-Cutters; and I do hereby declare the following to be a full, clear, and exact description thereof, reference being had to the accompanying drawings, making a part of this specification, in which—

Figure 1 is a top view of the feed-cutter.

Figure 2 is a vertical section passing longitudinally through the middle.

Figure 3 is a transverse section, showing the cutting apparatus; and

Figure 4 is a perspective view of the apparatus for feeding.

Like letters of reference refer to like parts of each.

The nature of my invention consists in the construction and adjustment of the knife of a feed-cutter and improved apparatus for feeding.

To enable others skilled in the art to make and use my invention, I will proceed to describe its construction and operation.

The box *x*, with its framework, varies from the usual form only sufficient to adapt itself to the devices to be described. The wheel *a* receives motion from a crank, *b*, or from a belt passing over it, or by other ordinary device, which it communicates, by cogs *a'* on the inner face of its outer rim, or by bevel or other equivalent gearing, to the pinion *c*, and through it and the shaft *d*, running in boxes *d'*, to the fly-wheel *e* and knife-block *f*. The wheels and gearing thus described are made of any known material adapted to such uses, and of any practicable known form. The knife-block *f*, however, I usually make of wood, of sufficient diameter and thickness to support the knife *g*, which is made commonly of steel, wholly or in part, or of other similar material, and sufficiently thick to secure the requisite stiffness. As represented in the drawings, and as I commonly make it, its outer or cutting edge *g'* is of the shape of an eccentric curve, the centre of the curve being at one side of the centre of revolution. By this means I bring the edge of the knife, as it revolves, with a gradually-increasing force against the straw or other material to be cut, and secure for it a cutting or slicing stroke, which, in such devices, is the most economical way of applying power. In the knife, as represented, are holes, or, more commonly, slots *h h'*, in any required number, the slot *h* of such direction and length that the knife *g* may be raised or lowered in the direction of the radius passing through the outer extremity of such slot, and through the knife at or near that part of its edge farthest distant from the centre of the shaft *d*. The slot *h'* commonly runs at an angle of nearly or exactly forty-five degrees to the radius passing through its outer extremity, and on the side of such radius toward the edge of the knife *g*, so that when the knife is lowered the narrow end of it will be carried outward from the centre of the shaft *d*, as well as downward in the direction of the slot *h*. The knife *g* is attached to the knife-block *f* by adjustable screws *i i*, with heads sufficiently broad to clamp the knife *g* firmly to its place. Thus adjusted the edge of the knife will always be in the same position with reference to the material to be cut. The knife *g* has also a projection, *p*, at or near the extremity of its longest radius. Immediately under the knife *g*, and attached to the front end of the feed-box *x*, is a curved bar, *l*, either grooved or having a notch, *l'*, on its upper and inner face, in which plays the projection *p*, and usually a part of the edge of the knife *g*, the radius of the curve of the bar *l* being equal to, or a little in excess of, the longest radius of the knife *g*. In the bottom of the box *x*, and a little in rear of the knife *g* and curved bar *l*, is a toothed feed-roller, *m*, so set that its teeth *s s s* shall project sufficiently above the bottom of the box *x* as to carry, as it revolves, the straw or other contents of the box forward under the knife *g*. In the bed or frame of the feed-box *x*, forward of the roller *m*, are attached wires or metallic strips *n n*, in any desirable number, which project back between the teeth *s s s*, fitting close to the upper-face of the roller *m*, and extending around it sufficiently far to keep their places, their function being to prevent the straw or other material to be cut from passing down forward of the roller *m*, and between it and the box *x*, in which it is set. Above the roller *m* is an adjustable keeper, *o*, which may be raised or lowered at pleasure, to compress the straw while being carried forward over the roller *m* and under the knife *g*. The feed-roller *m* is turned by a ratchet device, represented in fig. 4. On the shaft *d* is an eccentric, *y*, which communicates motion, through the bent lever *q*, its two arms *q' q''* being nearly or quite at right angles to each other, to the ratchet-bar *r*, which, in turn, is geared to

the ratchet-wheel r' , attached to the head of the roller m , so that, with the backward movement of the ratchet-bar r , the roller m will be turned forward. The pawl t prevents the backward motion of the roller, and the spring u holds the ratchet-bar r to its place. The feeding apparatus thus described is attached to the framework of the feed-cutter by bearings $z z' z''$. The crank δ I usually make not only adjustable but also removable, in case it should be desired to connect the wheel a , by a belt or otherwise, with a horse, steam, or other mechanical power.

The advantages of the knife as described over other knives in ordinary use consist, among other things, in ease and accuracy of adjustment, nothing being necessary thereto except loosening the screws $i i$, in the peculiarity of its cut or stroke, as above set forth, in the readiness with which it can be sharpened without being removed from its block f , and in its adaptedness to cut hay, straw, corn-stalks, or other similar product, ordinarily used for feeding. The projection p , usually blunt and not sharpened, cleans out the groove or notch l' with each revolution of the knife g .

I do not limit myself in my invention to the particular form of the knife above described, though I consider it the best; but having described the devices I employ, as shown in the drawings, I will proceed to show the applicability of the mode of manufacture and adjustment above set forth to knives the edges of which have other curves than the eccentric curve described. Knives whose edges g' give a snail-shell curve, or spiral or other similar curve, in which the radii increase in length in the direction opposite to the direction of the motion of the knife, I employ in substantially the same way and with a similar mode of adjustment. I also include in my invention knives the edges of which are of the shape of either half of a cycloidal or epicycloidal curve bisected in or near the line of its axis. A knife whose edge is of a parabolic or hyperbolic curve similarly bisected may be used in the same way, with the same or a similar adjustment; also, if the edge represents that part of an elliptic curve cut off by the intersection of the major and minor axes. In all the above cases I attach the knife to the knife-block f and shaft d by slots, as described, or otherwise, in such a way that lines from the centre of motion to the edge of the knife shall increase in length in the direction opposite to the direction of the motion of the knife as it revolves. In the same way, also, I attach and use a knife whose edge is the arc of a circle.

In adjusting the knives above described I do not limit myself in all cases to the use of the slots $h h'$, as I fasten the knives to the position described by the slots and screws, as set forth, or by other known means; nor do I restrict myself to the use of the knife-block f for the purpose of attaching the knife g to the shaft d , since, for this purpose, I employ, in addition thereto, any of the methods in common use for fastening circular-plate knives or saws to revolving shafts.

What I claim as my invention, and desire to secure by Letters Patent, is—

1. The rotary eccentric knife g , provided with slots $h h'$, in combination with the knife-block f , substantially as and for the purposes described.
2. The projection p on the knife of a feed-cutter, in combination with the curved bar l , provided with a notch or groove, l' , substantially as and for the purpose above described.

In testimony whereof I, the said HENRY HELM, have hereunto set my hand in presence of—

HENRY HELM.
